GARMENT FORM

Isidor Will Schwartzman, Jersey City, N. J., assignor to Protex Products Company, Jersey City, N. J., a corporation of New Jersey

Application September 10, 1936, Serial No. 100,095

8 Claims. (Cl. 223—68)

The present invention relates to garment forms, and more particularly, to forms of the type which are used in connection with hangers or stands for displaying dresses and other garments in show windows and stores.

In garment forms of this type the body of the form comprises a relatively thin, flat member having its longitudinal side edges shaped in simulation of the human figure whereby when the form is positioned inwardly of the garment, the latter by draping over the form conforms to the curvature of said side edges so that the garment has an appearance more closely approximating that which it is intended to have when worn. In this manner the garment is attractively displayed without the use of three dimensional forms, but one of the objections to the display of garments on forms of this type arises from the fact that in forms of this type as heretofore constructed, no provision is made for properly arranging the sleeves of the garment. It is, therefore, an object of the present invention to obviate this objection and for that purpose to provide a flat garment form with means for positioning the sleeves of the garment whereby the latter may be attractively displayed in relation to the body portion of the garment.

Another object of the invention is to provide improved means for adjustably and/or detachably mounting the garment form on the standard of the display stand in close relation thereto.

A further object is to provide means for attaching the form to the display in such manner that the attaching means, as well as the form, is invisible even when used with low neck garments.

The above objects of the invention, objects ancillary thereto, and other objects which might hereinafter appear will be fully understood from the following description considered with reference to the accompanying drawing forming a part of the present specification.

In the drawing:

Fig. 1 is a front view in elevation of the garment form of the present invention mounted on a display stand, and illustrating in dotted line a part of the garment;

Fig. 2 is a rear view in elevation of the upper part of the garment form mounted on the standard of the display stand;

Fig. 3 is a sectional view on an enlarged scale on the line 3—3 of Fig. 2;

Fig. 4 is a sectional view on the line 4—4 of Fig. 5, 2; and

Fig. 5 is a view similar to Fig. 3, showing a modification.

Referring to the drawing in detail, the garment form 10 comprises a relatively thin and flat body 12 of suitable material which is preferably relatively stiff, and accordingly may be made of wood, pasteboard, fibre board, similar materials. The longitudinal side edges 14 of the body 12 are curved to simulate approximately the curvature of the human figure. The upper end of the garment of the form 10 is preferably cut away to provide a recess 18 so that when the form is used with low neck garments it will not be visible through the low neck portion of the garment. It will be understood by those skilled in the art, that the garment form is inserted within the dress or other garment to be displayed and that the dress is suspended from the hanger 20 carried at the upper end of a vertical standard 22 of a display stand.

When the dress or other garment is thus mounted on the display stand with the garment form 10 inserted therein, the body portion of the garment conforms to the curvature of the form and is thus attractively displayed. In accordance with the present invention, however, provision is made for improving the attractiveness of the display, and more particularly, for positioning and securing the sleeves in such relation as to improve their appearance. For this purpose the garment form 10 is provided at the upper end thereof with arms 24 constructed and arranged to be inserted within the sleeves of the garment and also arranged to hold the sleeves in the desired position with relation to the body 12 of the garment form. As here shown, the arms 24, like the body 12, are relatively thin and flat and may be made of the same material as that of the body portion of the garment form. Said arms are pivotally connected at the upper ends of the bifurcated portions 26 of the body 12 by means of pivot pins 28. Spacing members 30 are interposed between the bifurcated portions 26 and the arms 24 thus providing clearance between the confronting surfaces of the body portion 12 and said arms.

The pivot pins 28 pass through the arms 24, spacing members 30, and bifurcated portions 26, and these parts are held together in face to face relation by the pivot pins whereby to provide substantial frictional engagement between the spacing members 30 and the contiguous surfaces of the arms 24 with the result that although the arms 24 can be readily rotated about the pivot pins 28 they tend to remain in the position in

which they are placed. By virtue of this construction, the arms 24 can be adjusted to the desired position for displaying the sleeves of the garment to the best advantage, and more specifically, by reason of the clearance between the arms 24 and the bifurcated portions 26, portions of the material of the sleeve may be inserted between said arms and the bifurcated portions of the garment form when it is desired to arrange 10 the sleeves close to the body portion of the garment. When the sleeve portions are inserted between the arms and the body of the garment form, the sleeves are held in the desired position without the use of pins or other fastening means, 15 since the space in which said sleeve portions are inserted is relatively narrow. Also, when displaying sleeveless dresses, gowns, or other garments, the arms 24 may be positioned to wholly overlie the body portion 12 of the form whereby they are 20 not exposed to view, but are concealed by the body portion of the garment.

For attaching the garment form 10 to the standard 22 of the display stand, there is provided a spring clamp 32 comprising a spring metal 25 plate 34 secured to the body 12, preferably at the waistline portion thereof, in any suitable manner, as for example, by rivets 36. The side portions of the plate are curved, forming confronting tube-shaped spring clamping members 38. The operation 30 of this clamp is obvious from the illustration and the foregoing description thereof, and it will be observed that the tube-shaped members 38 resiliently engage the standard 22 when the garment form 10 is mounted thereon. When thus mounted on the standard, the garment form 35 is positioned close thereto. This close position of the form permits the garment to hang in vertical position on the display stand and when the arms of the garment form are utilized for holding the garment sleeves in adjusted position, said sleeves 40 hang naturally from the shoulders in a vertical direction and are not offset from the vertical plane of the garment. It will be observed further that by means of this clamp the garment form 45 may be readily attached and detached from said standard and may be adjusted longitudinally thereof by a sliding movement of the clamp in relation to the standard.

In the form of the invention illustrated in Fig. 50 5, the clamp has auxiliary spring portions 39 which resiliently bear against the body portion 55 of the form. Portions of the dress may be secured between said spring portions 39 of the clamp and said garment form for retaining the 55 waist portion of the dress in the desired relation to the form.

It is thus seen that the construction herein shown and described is well adapted to accomplish the several objects of the present invention. 60 While this construction is considered the present preferred embodiment of the invention, it will be understood that the latter is capable of other embodiments and further that the construction herein shown or described may be modified in accordance with changes which will occur to those skilled in the art in view of the present disclosure. Accordingly, I do not wish to be limited precisely to the present construction or to any part thereof, except as may be required by the 65 appended claims and the prior art.

What I claim and desire to secure by Letters Patent is:

1. A garment display-form comprising a body portion adapted to be inserted within a garment 75 to be displayed, said body portion having means

secured thereto at one side thereof for removably and adjustably attaching the same to the vertical standard of a display stand having at its upper end a hanger from which the garment is displayed, and arm members attached to said body portion at the upper end thereof and arranged to be inserted within the sleeves of the garment through the arm holes of the latter, said arm members being movably mounted on said body portion of the form whereby the sleeves of the garment may be adjusted in relation to the hanger of said stand. 5

2. A garment display-form comprising a thin and flat body portion adapted to be inserted within a garment to be displayed, said body portion 15 having means secured thereto at one side thereof for removably and adjustably attaching the same to the vertical standard of a display stand having at its upper end a hanger from which the garment is displayed, and thin and flat arm members pivotally attached to said body portion at the upper end thereof and arranged to be inserted within the sleeves of the garment through the arm holes of the latter, said arm members being movably mounted on said body portion of the form whereby the sleeves of the garment may be adjusted 20 in relation to the hanger of said stand. 25

3. A garment display-form comprising a thin and flat body portion adapted to be inserted within a garment to be displayed, said body portion 30 having means secured thereto at one side thereof for removably and adjustably attaching the same to the vertical standard of a display stand having at its upper end a hanger from which the garment is displayed, said body portion having upwardly projecting laterally spaced portions defining a central recess in the upper part of said body portion arranged to register with the neck opening of the garment when the form is in predetermined position on said standard in relation 35 to said hanger, and thin and flat arm members pivotally attached to the upper ends of said laterally spaced form portions at opposite sides of said recess, arranged to be inserted within the sleeves of the garment through the arm holes of the latter, said arm members being movably mounted on said body portion of the form whereby the sleeves of the garment may be adjusted 40 in relation to the hanger of said stand, and spring means on the rear of said body portion for releasably securing portions of the garment at the 45 rear of the form in predetermined adjusted relation thereto. 50

4. A garment-display device comprising a vertical standard having a hanger at its upper end, 55 and a display form comprising a body portion adapted to be inserted within a garment to be displayed, said body portion having means secured thereto at one side thereof for removably and adjustably attaching the same to said standard below said hanger, and arm members attached to said body portion at the upper end thereof and arranged to be inserted within the sleeves of the garment through the arm holes of the latter, said arm members being movably 60 mounted on said body portion of the form whereby the sleeves of the garment may be adjusted in relation to the hanger of said standard. 65

5. A garment-display device comprising a vertical standard having a hanger at its upper end, 70 and a display form comprising a thin and flat body portion adapted to be inserted within a garment to be displayed, said body portion having means secured thereto at one side thereof for removably and adjustably attaching the same to 75

5 said standard below said hanger, and thin and flat arm members pivotally attached to said body portion at the upper end thereof and arranged to be inserted within the sleeves of the garment through the arm holes of the latter, said arm members being movably mounted on said body portion of the form whereby the sleeves of the garment may be adjusted in relation to the hanger of said standard.

10 6. A garment display-form comprising a body portion adapted to be inserted within a garment to be displayed, said body portion having means secured thereto at one side thereof for removably and adjustably attaching the same to the vertical standard of a display stand having at its upper end a hanger from which the garment is displayed, and arm members attached to said body portion at the upper end thereof and arranged to be inserted within the sleeves of the garment through the arm holes of the latter, said arm members being movably mounted on said body portion of the form whereby the sleeves of the garment may be adjusted in relation to the hanger of said stand, said attaching means having spaced confronting portions adapted to grip said standard therebetween and movable into and out of engagement with said standard in a direction transversely thereof.

15 7. A garment display-form comprising a thin and flat body portion adapted to be inserted within a garment to be displayed, said body portion having means secured thereto at one side thereof for removably and adjustably attaching the same to the vertical standard of a display stand having at its upper end a hanger from which the

garment is displayed, and thin and flat arm members pivotally attached to said body portion at the upper end thereof and arranged to be inserted within the sleeves of the garment through the arm holes of the latter, said arm members being movably mounted on said body portion of the form whereby the sleeves of the garment may be adjusted in relation to the hanger of said stand, said attaching means having spaced confronting portions adapted to grip said standard 5 therebetween and movable into and out of engagement with said standard in a direction transversely thereof.

10 8. A garment display-form comprising a thin and flat body portion adapted to be inserted within a garment to be displayed, said body portion having means secured thereto at one side thereof for removably and adjustably attaching the same to the vertical standard of a display stand having at its upper end a hanger from which the garment is displayed, and thin and flat arm members pivotally attached to said body portion at the upper end thereof and arranged to be inserted within the sleeves of the garment through the arm holes of the latter, said arm members being movably mounted on said body portion of the form whereby the sleeves of the garment may be adjusted in relation to the hanger of said stand, said attaching means having spaced confronting portions adapted to grip said standard 15 therebetween and movable into and out of engagement with said standard in a direction transversely thereof.
